UNITED STATES PATENT OFFICE.

FRANK R. CHESTER, OF ASBURY PARK, NEW JERSEY.

COIN DETECTOR.

Application filed November 29, 1922. Serial No. 604,047.

To all whom it may concern:

Be it known that I, FRANK R. CHESTER, a citizen of the United States, and a resident of Asbury Park, in the county of Monmouth and State of New Jersey, have invented a certain new and Improved Coin Detector, of which the following is a full, clear, and exact description.

This invention relates to coin-detectors, and more particularly aims to provide a new and useful coin-responsive electric system for association with apparatus of any kind and for any purpose, and to be operable on receipt of a genuine and unadulterated coin and one of the prevised denomination (hereinafter called the prevised coin); such system to act as a detector of the character of the coin submitted thereto before such coin goes to said apparatus.

It has previously been suggested to employ in electric coin-detecting systems, as in U. S. patent to Kitsee, No. 790,641, a primary and a secondary circuit, each circuit having a plurality of coils in series, and these coils arranged so that each coil in one circuit is associated inductively with one coil of the other circuit to provide a pair of what may be termed balancer-transformers. According to the Kitsee patent, it has also been proposed to use one of the transformers as what may be termed a tester transformer, and accordingly to arrange the same adjacent to the coin chute so that the coin inserted in the latter will have a certain inductive effect on the system depending on its metallic mass and the metallic elements making up such mass—which effect is employed in the Kitsee system to permit or prevent the sounding of a distant signal telephonically, as may be very useful in connection with coin-box telephone stations.

According to the system just described, however, the coin intercepted by the detent in the chute, whether such coin be the prevised one or some other, is not automatically released from the system but must be manually released.

The present invention has as its principal object the provision of a system of the balancer-transformer type, but one in which the prevised coin or any other, or even a slug, will be instrumental in automatically restoring the system immediately following the functioning of the latter as a detector of the character of the coin last mentioned,

thus dispensing with the need of any human attendant whatsoever, as is desirable if not economically necessary in practically all coin actuated apparatus except pay-
station telephones.

The object last mentioned is attained by not only, as in Kitsee, (a) providing primary and secondary circuits; (b) interposing in each circuit two coils in series; (c) arranging such coils so that each coil in a circuit is one of two inductively reactant coils of one of two pairs of transformers; (d) winding the coils of such two transformers so that when one transformer is adjusted to a predetermined inductive relation, the coin inductively adjacent the other or tester transformer balances or unbalances oppositely flowing potential differences in the secondary circuit; (e) providing a coin chute to guide the coin toward inductive relation to the tester transformer and associating with said chute a coin detent; and (f) providing an electro-magnet means or the like for moving said coin detent;—but by providing certain new and useful variation of the system, characterized chiefly by the features (g) that said electro-magnet means is interposed in one of the primary and secondary coils, but preferably the latter, and so in series with the coils therein, whereas the same means of Kitsee is in a third circuit, the telephone circuit; and (h) that said electro-magnet means functions to move the coin detent solely as the result of the balanced or unbalanced condition of the secondary circuit, and hence is an automatically functioning element of the new system, whereas the same means of Kitsee is totally unaffected by the condition of the secondary circuit and is merely a manually operable adjunct in the Kitsee system.

Thus the coin-controlling system of the present invention does not require any human attendant whatsoever, especially since, as the invention is preferably carried out, the coin detent is in inoperative position in the main coin chute at all times except on the occurrence of a certain contingency, to wit, the insertion of a coin other than the prevised one, whereas according to the Kitsee system the detent device is operative at all times except upon the occurrence of a certain contingency, to wit, the manual closing of a circuit to throw the coin detent to inoperative position.

- Another object of the present invention is to provide, as is desirable, diverging coin-guiding means beyond the main chute, with the parts, and particularly the detent, so arranged that the detent is really only a detent for one of the two diverging coin-guiding means below the chute, whereby automatically, if the coin is the prevised one, the detent will either remain immovable, to pass the coin on toward, if desired, the usual locked receptacle or the like, and in the course of such travel release the turnstile, vending machine, or whatever particular apparatus is associated with the coin-detecting system, or, if the coin is not the prevised one, the detent will be moved by the electro-magnet means to preclude the coin from passing on toward said apparatus, perhaps to return the coin to the patron.
- 20 A further object of the invention is to provide a system which, unlike the Kitsee system, does not require the manual insertion of an extra inductive device into predetermined adjacency to the transformer other than the tester transformer each time the system is to function. In this connection, still another object of the invention is to adapt the transformer for convenient and prevised adjustment or readjustment at any time, but so as thereafter to function without further attention during employment of the system over a long period of time and for a great plurality of successively deposited coins.
- 30 With the foregoing and other objects in view, the invention consists in the features of construction, combinations of elements and arrangements of parts which will be exemplified in the description hereinafter set forth.
- 35 In the accompanying drawings, wherein is shown an illustrative example of a possible embodiment of the invention as at present preferred.
- 40 Fig. 1 is a schematic view of such embodiment;
- 45 Fig. 2 is a vertical section through the tester coil set, showing the coin chute and appurtenant parts; and
- 50 Fig. 3 is a view similar to Fig. 2, but taken on the line 3—3 of Fig. 2;
- 55 Similar reference characters refer to similar parts throughout the several views.
- As heretofore proposed, the system illustrated includes a primary circuit 5 and a secondary circuit 6. The primary circuit includes in series two coils 7 and 8 and the secondary circuit includes in series two coils 9 and 10. The coils 8 and 10 form one of the transformers, which may be termed the standard transformer, by which is meant a transformer establishing an inductive standard by which the coin is to be tested; and the coils 7 and 9 form the other or tester transformer, that is, the one with which is asso-

ciated a coin guiding means or chute 11. If the source of current supplied to the primary circuit delivers alternating current the interrupter 12 will not be required; but if a battery 13 is employed as here for such source of current or if the current in any manner delivered is direct, the interrupter may be used to establish a pulsating current in the primary circuit and hence permit the coils 7 and 8 to have varying magnetic fields relative to the coils 9 and 10 as in ordinary transformers. In order that such fields will simultaneously tend to induce oppositely flowing currents in the secondary circuit 6, the coils 9 and 10 are oppositely wound. 80

Said chute 11 has two diverging continuations as shown and marked 11^a and 11^b in Fig. 3. By the term "main chute" as hereinafter used is meant the chute 11 and its continuation 11^a, while the chute 11^b will be considered an entirely different chute and referred to as the auxiliary chute.

The main features of the new system of the present invention are four, although various other novel details will be hereinafter specifically pointed out or obvious.

In the first place, a coin-detent 15 is movably associated with the chute 11 and just below coil 7, as by means of fixing same on a pivotally mounted shaft 16 so that the detent is normally in inoperative condition relative to the main chute 11—11^a. Such detent is thus normally disposed as by a leaf spring 17 (adjustable if desired by a set-screw) to permit a coin to pass beyond the position where the coin has the maximum inductive effect on coil 7 immediately after the coin has been tested; as it will be seen that whether the coin-detent stays as shown in Fig. 3 or is thrown to the broken line position 15^a by means hereinafter described, according to whether or not the coin is the prevised one, the coin will pass either into the chute 11^b or the continuation 11^a of the main chute 11. It is again expressly emphasized that normally the detent is in inoperative position relative to the main chute 11—11^a. 105

If the coin deposited by the patron in the chute 11 is the prevised coin, the same may thus descend by way of one of the chutes 11^a and 11^b to enter a suitable lock-box (not shown), or if some other object, the same may descend by one or the other of such chutes to enter any suitable compartment (also not shown) or be returned to the patron by any suitable outlet. Otherwise stated, the detent 15 never needs a human attendant to manually move the same at any time after a coin has been deposited in the upper end of the chute, nor need the detent ever be manually adjusted in preparation for the deposit of a coin. 115

It is important that the design of the system be such that with the primary circuit 5 130

(which here is open normally, that is, when no coin is in the chute 11) closed, the oppositely wound coils 9 and 10 of the secondary circuit 6 are normally unbalanced, that is, 5 opposing currents induced in these coils by induction from coils 7 and 8 are unequal, and so there is a current flow in the secondary circuit whenever the primary circuit is closed, unless the coin then in chute 11 is 10 the revised coin, in which case the coils 9 and 10 are balanced, but due solely to the inductive adjacency of said coin, against any current flow in the secondary circuit.

The means for utilizing such a flow of 15 current in the secondary coil to temporarily throw the detent 15 to the position 15^a includes an electro-magnet 18 interposed here in the secondary circuit 6. Such means for controlling the detent, constituting the second of the four main features of novelty above mentioned further includes in the present case, and in order to make the movements of the coin-detent responsive to an exceedingly small current flow between the 20 coils 9 and 10, and so make the new system exceedingly accurate in coin detecting, an arrangement whereby the electro-magnet 18 is not the direct magnetic agent for moving the detent, but instead is really a relay for 25 closing a third but wholly manually unattended circuit 19; this third circuit being normally open and closed only when relay 18 is energized sufficiently to attract its very light armature 20, which armature is a circuit-closing means as illustrated for the circuit 19. In said circuit 19 is interposed an electro-magnet 21 which, when energized 30 from its own special source of current 22, will have sufficient strength to move the detent positively and surely the proper amount in accordance with the design and intended 35 operation of the particular system installed. In the present case, when the electro-magnet 21 is energized, the detent is moved to the 40 position shown at 15^a by means of an arm 23 acting as an armature for the electro-magnet 21, such arm being offset from the shaft 16 on which the coin-detent is mounted. This results in moving the coin-detent 45 against spring 17 from inoperative to operative position relative to the main chute 11—11', in the sense that the detent is moved to preclude the coin from entering the continuation chute 11^a of the main chute and 50 permit the coin to enter the auxiliary chute 11^b. The continuation chute 11^a may lead to a suitable lock-box (not shown) intended to receive only the revised coins, and the chute 11^b may be provided to return the inserted object to the patron if such object 55 not be the revised coin.

The third of the more important features 60 of the new system as above specified, is not only the normally open condition of one of the circuits 5 and 6 when one of such cir-

cuits has interposed therein a relay 18 or any electro-magnet means to actuate a train of means to operate the coin-detent as just indicated, but the use of a normally operative coin-interceptor in the chute 11, as the 70 interceptor indicated at 24, adapted to be moved from its normal illustrated location by the passage of a coin through the chute, thereby temporarily to close the normally open primary circuit 5. According to this 75 arrangement the new system involves really a plurality of coin-interceptors, each movably associated with the coin guiding means; since the coin-detent 15 is really also a coin-interceptor. The interceptor 24 is here a 80 single member pivotally mounted as at 25 and normally urged by spring 26 toward protrusion into the chute; the part thus protruded being so shaped and arranged as illustrated, that is, being elongated lengthwise of the chute, that during an appreciable travel of the coin down the chute such member is moved and held to a position such that a contact 27 carried thereby temporarily closes the primary circuit at the 85 normally open gap 28. It will be seen from Fig. 2 that during said travel of the coin it is moved into maximum inductive relation to the coils 7 and 9 of the tester transformer, and hence will before the coin may 90 pass beyond the interceptor 24 thereby to cause an automatic reopening of the primary circuit, the coin-detent 15 will remain as shown or be moved as the result of electric coin detection according to the invention. In the present case, as is preferable, the coin does not release the interceptor 24 to permit the latter to reopen the primary circuit until the coin has safely entered either the chute 11^a or 11^b, according to 95 whether the two transformers are inductively balanced or unbalanced. Thus, immediately after the coin is directed into its proper chute 11^a or 11^b, the consequent reopening of the primary circuit automatically restores the entire system including an automatic redisposition of the coin-detent 15 to inoperative position (if necessary) in readiness for the approach of another patron.

The fourth of the main important features of the new system as above specified is the arrangement of the system such that the system may be readily set for a coin of any desired denomination, and once set may act as predetermined and without further attention or human attendance for a multiplicity of such coins sporadically inserted in the chute 11. That is to say, once the system is adjusted to the inductive condition required according to the design of the system to render the intended coin, and only the intended coin, effective to balance the two transformers when the primary circuit 5 is temporarily opened by the inter- 115 120 125 130

ceptor 24, the system thereafter automatically operates entirely without the interpolation of a human agent. To the end just indicated both coils 9 and 10 of the system are associated with convenient means for varying as desired the induction between coils 7 and 9 and between coils 9 and 10. Such means in the present case includes, as shown best in Fig. 1, a pair of sleeve-like slidable mountings 29 and 30 one carrying each of the coils 9 and 10. Set-screws are provided on these mountings as indicated, to hold the coils 9 and 10 any selected distances from coils 7 and 8, which latter coils are fixed, the first on the chute 11 and the second on a suitable fixed support 31. The operation of properly setting the standard transformer comprising the coils 8 and 10 for a prevised coin is substantially as follows:

One of the prevised coins is dropped into the chute 11 and automatically detained as indicated in Fig. 2 at 14, as by way of an auxiliary temporary detent, as a suitable pin (not shown) inserted into the chute by way of a hole 32; thus holding the coin in maximum inductive adjacency to the coil 7 and also maintaining the interceptor 24 in position to close the normally open gap 28 in the primary circuit 5. Thereupon, one or both the coils 9 and 10 are moved relative to coils 7 and 8 until the coin-detent 15 moves to inoperative position, that is to the full-line position shown in Fig. 3. The system is now delicately, yet very durably and reliably adjusted for proper operation relative to the prevised coin; and the coin 14 in chute 11 may be suitably released from said chute merely by removing the temporary auxiliary detent above mentioned.

Unless deliberately intended to be induction-varying factors in the system, the parts closely adjacent the four coils are, of course, made of fibre, wood, bronze, or some other suitable non-inductive material; and with this explanation and the ones foregoing, the operation of the system in service should be clearly understood.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It will also be understood that the language used in the following claims is intended to cover all the generic and specific features of the invention herein described and all statements of the invention which, as a matter of language, might be said to fall therebetween.

I claim:

1. In an electric coin-detector system, the combination of a primary circuit including in series a first coil and a second coil, a secondary circuit including in series a first coil and a second coil, one of said circuits being normally open said two first coils being in inductive relation and said two second coils being in inductive relation, the two coils in one of said circuits being in balanced relation in said circuit, a coin chute for guiding a coin into inductive relation to one of the sets of inductively related coils, a coin detent movably associated with the chute, means for moving said detent, actuated when the open circuit is closed, and means for temporarily closing said open circuit and actuated by the deposited coin before the latter reaches said detent.

2. In an electric coin-detector system, the combination of a primary circuit including in series a first coil and a second coil, a secondary circuit including in series a first coil and a second coil, said two first coils being in inductive relation and said two second coils being in inductive relation, the two coils in one of said circuits being in balanced relation in said circuit, a coin chute for guiding a coin into inductive relation to one of the sets of inductively related coils, a coin detent movably associated with the chute, and means for moving said detent, the means last mentioned including electro-magnet means interposed in one of said circuits, the means for moving said detent also including a normally open third circuit adapted to be closed by said electro-magnet means, said last-mentioned circuit having interposed therein a second electro-magnet means adapted on an energization thereof to cause such movement of the detent.

3. In an electric coin-detector system, the combination of a primary circuit including in series a first coil and a second coil, a secondary circuit including in series a first coil and a second coil, said two first coils being in inductive relation and said two second coils being in inductive relation, the two coils in one of said circuits being in balanced relation in said circuit, a coin chute for guiding a coin into inductive relation to one of the sets of inductively related coils and then immediately out of such inductive relation, one of said circuits being normally open, and means actuated by the coin in passing through such chute to momentarily close the circuit last mentioned.

4. In an electric coin-detector system, the combination of a primary circuit including in series a first coil and a second coil, a secondary circuit including in series a first coil and a second coil, said two first coils being in inductive relation and said two second coils being in inductive relation

inductively affect the same, and a coin detent associated with said means, said detent being normally inoperative.

10. In an electric coin-detector system, the combination of a primary circuit including in series a first coil and a second coil, a secondary circuit including in series a first coil and a second coil, said two first coils being in inductive relation and said two second coils being in inductive relation, the two coils in one of said circuits being in balanced relation in said circuit, means for guiding a coin relative to the system to inductively affect the same, one of said circuits being normally open, a plurality of movable coin interceptors associated with said guiding means at different levels, closing means for such normally open circuit controlled by the position of the upper interceptor, and normally inoperative means adapted to move the lower interceptor and rendered operative by the closing of such normally open circuit.

11. In an electric coin-detector system, the combination of a primary circuit including in series a first coil and a second coil, a secondary circuit including in series a first coil and a second coil, said two first coils being in inductive relation and said two second coils being in inductive relation, the two coils in one of said circuits being in balanced relation in said circuit, means for guiding a coin relative to the system to inductively affect the same, one of said circuits being normally open, means for closing said normally open circuit, means for adjusting the coils whereby said oppositely wound coils will be precisely balanced when the revised coin is in said guiding means and said normally open circuit is closed, adjustable auxiliary guiding means for receiving a coin from the first guiding means, and means, for adjusting such auxiliary means when such coin fails to balance said oppositely wound coils.

12. In an electric coin detector system, the combination of primary and secondary circuits one normally open and one including a plurality of coils in series, said coils being constituted, wound and spaced so as to tend to set up oppositely flowing currents in said circuit when both coils are inductively affected, and means whereby the introduction of a coin in the system will close said open circuit and inductively affect the same there being also provided means to guide such coin along a predetermined path and means brought into operation by a coin of a different inductive value to guide the latter coin along a different path.

13. In an electric coin detector system the combination of primary and secondary circuits one normally open and one including a plurality of coils in series, said coils being constituted, wound and spaced so as

to tend to set up oppositely flowing currents in said circuit when both coils are inductively affected, and means whereby the introduction of a coin in the system will close said open circuit and inductively affect the same, there being provided means for automatically reopening the circuit last mentioned after passage of the coin beyond its location of maximum inductive effect.

14. In an electric coin detector system, the combination of primary and secondary circuits one normally open and one including a plurality of coils in series, said coils being constituted, wound and spaced so as to tend to set up oppositely flowing currents in said circuit when both coils are inductively affected, and means whereby the introduction of a coin in the system will close said open circuit and inductively affect the same, there being also provided means to guide such coin along a predetermined path and means brought into operation by a coin of a different inductive value to guide the latter coin along a different path, means for reopening the circuit last mentioned, and means for restoring said deflecting means, the two means last mentioned automatically operating after passage of a coin beyond its location of maximum inductive effect.

15. In an electric coin-detector system, the combination of primary and secondary circuits one normally open and one including a plurality of coils in series, said coils being constituted, wound and spaced so as to tend to set up oppositely flowing currents in said circuit when both coils are inductively affected, means whereby the introduction of a coin in the system will close said open circuit and inductively affect the same, said means including relatively movable contacts in said open circuit, and means actuated by the introduction of a coin into the system for moving said contacts relatively to cause them in and by themselves to close said gap.

16. In an electric coin-detector system, the combination of primary and secondary circuits one normally open and one including a plurality of coils in series, said coils being constituted, wound and spaced so as to tend to set up oppositely flowing currents in said circuit when both coils are inductively affected, and means whereby the introduction of a coin in the system will close said open circuit and inductively affect the same, said system including a coin interceptor movable from an effective to an ineffective position, and vice versa, said means including a switch thrown and held to a certain setting by and during movement of a coin in the system, said switch while thus thrown and held closing said open circuit.

17. In an electric coin-detector system, the combination of primary and secondary circuits one normally open and one including

a plurality of coils in series, said coils being constituted, wound and spaced so as to tend to set up oppositely flowing currents in said circuit when both coils are inductively affected, and means whereby the introduction of a coin in the system will close said open circuit and inductively affect the same, said system including a coin interceptor movable from an effective to an ineffective position, and vice versa, said means including a switch actuated by the coin following its introduction into the system, said switch when thus actuated closing said open circuit through conductors entirely additional to said interceptor.

FRANK R. CHESTER.
